THOMAS H. KANE, OF YOUNGSTOWN, OHIO, ASSIGNOR TO TRUSCON STEEL COMPANY, OF YOUNGSTOWN, OHIO, A CORPORATION OF MICHIGAN.

SPACER FOR CONCRETE REINFORCEMENT.

Application filed June 1, 1925. Serial No. 33,966.

The present invention relates to reenforcing elements for concrete structures and more specifically to such elements for reenforcing concrete columns.

Heretofore, reenforcing elements for columns, commonly called "hooping", has been made by winding a helix of metal rod and spacing the flights thereof by means of a plurality of bars of T section having notches in the web portion in which notches the flights were placed and secured. This forms a cylindrical reenforcement having two or more of the longitudinal spacer bars.

One of the objections to this form of spacer is that it necessarily has a fixed longitudinal dimension and therefore has to be used in factory fixed lengths or cut off with considerable trouble and expense.

Among the objects of the present invention therefore, is a reenforcement spacer that will permit adjustment of its length to a considerable degree, either for lengthening or shortening.

Another object is a spacer that may be easily adapted to hooping of various pitches and diameters.

Still another object is a spacer which is suitable for use with hooping made of different gauges of metal rod.

Other objects will readily appear to those skilled in the art upon reference to the following description and claims in which:

Fig. 1 shows a portion of column reenforcement with one spacer in place and another in process of application.

Fig. 2 is a perspective view of the spacer.

Fig. 3 is a similar view of the locking rod.

Fig. 4 is an end view of a reenforcing element with the spacer on one side secured and that on the other about to be secured.

As indicated in the drawings, the "hooping" used with the present spacer consists of a helix or spiral 10 of metal rod, and the spacer consists of the two parts shown in Figs. 2 and 3.

The part shown in Fig. 2 is the spacer proper and will be so called, being designated by the numeral 11. This spacer before application to the spiral 10 consists of a small rod bent to form narrow loops 12, sufficiently wide to accommodate the largest gauge of spirally wound rod with which it is to be used. The loops 12 are spaced apart by straight portions 13, the distance between the

flights of the spiral 10, and, as loops 12 may be relatively long, this space will admit of considerable variation after the spacer has been formed, merely by opening or closing loops 12 a small distance.

In order to facilitate the application of the spacer to a spiral, after the loops 12 have been formed they are all bent over in the same direction, forming the angle at a point somewhere near their middle, as indicated in Figs. 2 and 4.

The application of the spacer 11 to a spiral 10 consists in sliding the loops 12 over the several flights of the spiral, then placing a straight rod 14 such as that shown in Fig. 3, inside of the spiral 10 and in the angle of the spacer 11 against the several flights. Then by means of a flat bar, such as 15, the parts 13 may be bent around rod 14, as indicated most clearly in Figs. 1 and 4, locking the spacer 11 securely on the spiral.

Fig. 4 shows at A, in full lines, the spacer 11 before being locked and, in dotted lines, its form after locking. At B is shown, in full lines, the spacer 11 after being locked, and, in dotted lines, before being locked.

It should be noted that, while the spacer 11 may be elongated or shortened without cutting or splicing to vary the total length or distance between the centers of the loops 12, after the rod 14 has been placed in position and the portions 13 of spacer 11 bent around it to lock the several parts together, it will be fixed in length for all ordinary handling, such as shipping or placing in position.

Having now described the invention and the preferred embodiment of the same, it should be understood that it is not to be limited to the precise form shown and described, but only by the scope of the claims which follow:

Claims.

1. A spacer for the flights of concrete reenforcing "hooping" consisting of a rod bent to form a series of narrow loops spaced apart the distance required between the flights and a rod about which may be bent the portions of the rod between the loops.

2. In combination concrete reenforcing "hooping", a spacer consisting of a rod bent to form a series of spaced apart loops each adapted to embrace a flight of said hooping, and a locking rod adapted to span said loops containing said flights and around which is

adapted to be bent that portion of the spacer rod between loops.

3. As a new article of manufacture a spacer for concrete reenforcing hooping consisting of a rod bent to form a series of spaced narrow parallel loops having the portions of the rod between the loops substantially in alignment, the loops being bent intermediate their ends and in the same direction.
4. As a new article of manufacture a spacer for concrete reenforcing hooping consisting of a rod bent to form a series of spaced narrow parallel loops having the portions of the rod between the loops substantially in alignment, the loops being bent to form obtuse

angles intermediate their ends and in the same direction.

5. Spacing means for concrete reenforcing hooping consisting of a member adapted to be arranged longitudinally of the hooping and provided with substantially equispaced means for attachment to the several flights of said hooping, said member being capable of elongation or shortening whereby to increase or diminish the distance between the attaching means, and means for fixing the length and distances between the attaching means when said spacer is applied to said hooping.
